(57) **CLAIM**

The ornamental design for a multiple mount accessory rail, as shown and described.

DESCRIPTION

FIG. 1 is a front view thereof;

FIG. 2 is a rear view thereof;

FIG. 3 is a left-side view thereof;

FIG. 4 is a right-side view thereof;

FIG. 5 is a top plan view thereof;

FIG. 6 is a bottom plan view thereof;

FIG. 7 is an isometric perspective view of the multiple mount accessory rail;

FIG. 8 is an exploded front view thereof; and,

FIG. 9 is an exploded perspective view thereof.

The broken line showing the fasteners is included for the purpose of illustrating environmental structure and forms no part of the claimed design.
